No. 735,333.

PATENTED AUG. 4, 1903.

W. J. BAILEY.
CIGAR PIERCING DEVICE.
APPLICATION FILED SEPT. 30, 1902.

NO MODEL.

Fig. 1

UNITED STATES PATENT OFFICE.

WILLIAM J. BAILEY, OF NEWARK, NEW JERSEY.

CIGAR-PIERCING DEVICE.

SPECIFICATION forming part of Letters Patent No. 735,383, dated August 4, 1903.

Application filed September 30, 1902. Serial No. 125,343. (No model.)

To all whom it may concern:

Be it known that I, WILLIAM J. BAILEY, a citizen of the United States, residing at Newark, in the county of Essex and State of New Jersey, have invented certain new and useful Improvements in Cigar-Piercing Devices; and I do hereby declare the following to be a full, clear, and exact description of the invention, such as will enable others skilled in the art to 5
10 which it appertains to make and use the same, reference being had to the accompanying drawings, and to figures of reference marked thereon, which form a part of this specification.

15 This invention relates to a novel construction of cigar-piercing device, the main object of the invention being to provide a cigar-piercing device of a simple, neat, and cheap construction, the parts of which are arranged 20 in such a manner that they can be easily manipulated and the cigar pierced in the side at or near the end of the cigar which is placed in the mouth without the necessity of cutting away a portion of the drawing end of the cigar.

25 Other objects of this invention not at this time more particularly mentioned will be clearly evident from the following detailed description of my present invention.

The invention therefore consists in the novel 30 cigar-piercing device hereinafter more particularly described, and, furthermore, this invention consists in the various novel arrangements and combinations of the parts, as well as in the details of the construction thereof, 35 all of which will be fully set forth in the following specification and then finally embodied in the clauses of the claim, which are appended to and form a part of this specification.

The invention is clearly illustrated in the 40 accompanying drawings, in which—

Figure 1 is a plan or top view of a cigar-piercing device embodying the principles of this invention. Fig. 2 is a horizontal section of the same, illustrating one arrangement of the piercing means within the chambered casing of the device; and Fig. 3 is a side view of the same. Fig. 4 is a transverse vertical section taken on line 4-4 in Fig. 2; and Fig. 5 is a similar section taken on line 5-5 in said 45 50 Fig. 2, in both instances looking in the direction of arrow α . Fig. 6 is a horizontal sectional representation of a cigar-piercing de-

vice of a slightly-modified form of construction, and Fig. 7 is a transverse vertical section taken on line 7-7 in said Fig. 6 looking in the direction of arrow γ . Fig. 8 is a plan or top view, and Fig. 9 a horizontal sectional representation, of a cigar-piercing device of another modified form of construction, but still embodying the leading features of my present invention.

Similar characters of reference are employed in all of the said hereinabove-described figures to indicate corresponding parts.

In the said drawings the reference character 1 indicates the complete cigar-piercing device, the same comprising a chambered casing consisting, essentially, of a pair of shells 2 and 3. These shells 2 and 3 may be of any suitable configuration in outline, that herein shown being of a circular shape and the shells being provided with the marginal flanges 4 and 5, respectively, whereby the two shells may be fitted over each other in the manner of an ordinary box body and cover, as illustrated in some of the figures of the drawings. In order that the said two shells may be positively retained one upon the other, the one shell, as 3, may be provided in its flange 5 with a projection or projections 6, which is 70 sprung into a correspondingly-placed opening or openings 7 in the flanges 4 of the other shell, 2, as clearly illustrated in Figs. 2, 4, 7, and 9; but of course it will be evident that the said shells may be provided with any other suitably-constructed holding or fastening means 75 for positively connecting the two shells together. As will be seen from an inspection of Figs. 2, 4, and 5, the shell 3 is provided in its bottom with inwardly-projecting lips or projections, forming suitable guides 8 for the purposes to be presently described. These guides 8 are in alinement with centrally-disposed openings 9 in the main bodies of the respective shells 2 and 3, said guides 8 being also in alinement with openings 10 in the flanges 4 and 5 of said shells, as shown. Slidably arranged between the said shells 2 and 3 and between each pair of guides 8 is a slide 11, each slide being provided with a suitable finger-piece 12, arranged within and extending from the opening 10 in each side of the casing 1, suitable stops 13 being formed upon each slide 11 to limit the outward movement of each slide and prevent 80 85 90 95 100

its withdrawal from the chambered casing 1. Each slide 11 is also provided upon its inner end 14 with a suitably-constructed piercing member or needle 15, preferably of an ovoid shape in cross-section, a suitable spring 16 being arranged between the stops 13 on the one side of the two slides, as indicated more particularly in Fig. 2 of the drawings. The tendency of this spring 16 is to normally force 10 the two slides 11 in opposite outward directions, so as to bring the stops 13 against the inner and opposite surfaces of the flange 5 of the shell 3, as shown, and thereby withdraw the piercing members or needles 15 under normal conditions away from the openings 9 in the said shells 2 and 3.

The piercing device is used in the following manner: The pointed or drawing end of a cigar is inserted in either of the said openings 9 so as to bring this end portion of the cigar directly between the oppositely-placed points of the piercing members or needles 15. The device or casing 1 being held in the one hand by the placing of the thumb upon the 25 finger-piece of the one slide and a finger upon the finger-piece of the other slide, pressure is placed upon the ends of the said finger-pieces in opposite directions. The two piercing members or needles 15 are thereby forced 30 directly into the opposite sides of the cigar, the several parts assuming the positions indicated in the dotted outlines in said Fig. 2. When the pressure is again removed from the ends of the finger-pieces of the slides 11, the 35 said spring 16 causes the parts to once more assume their normal initial position, whereby the piercing members or needles 15 are withdrawn from the sides of the cigar, leaving the cigar provided with suitable perforations 40 in its sides, without necessitating the cutting away of the pointed end of the cigar and still permitting a proper draft through the cigar and an enjoyable smoke.

In place of the slides 11, provided with the 45 stops 13 and the guides 8, (represented in the construction illustrated in Figs. 1 to 5, inclusive,) I may employ in place of the said guides 8 suitable projections 17, which are struck up in the bottom of the shell 3 and extend into 50 the chamber formed by the two shells 2 and 3. In this case each slide 11 is made with an opening 18, into which the projection 17 extends, as illustrated in Figs. 6 and 7, the said slides 11 being also provided with suitable notches 55 19 for the reception of the ends of the spring 16, which is sprung into place and is held by the said notches, as will be clearly seen from an inspection of said Fig. 6. In lieu of either of these constructions represented in said 60 Figs. 1 to 7, inclusive, the cigar-piercing device may be made as indicated in Figs. 8 and 9. In that case all the guides or projections are dispensed with, each slide 11 being provided with a downwardly-extending arm 20, 65 each arm being secured to the bottom of the shell 3 by means of pivots or pins 21, on each of which each arm 20 of the respective slides

is capable of an oscillatory motion when pressure is applied to the ends of the finger-pieces of said slides. To return the said slides to 70 their normal initial positions after the pressure has been released from the finger-pieces, a spring, as 22, is arranged between the two arms 20, as shown in Fig. 9, and the said spring acting to force a stop 23 on each slide against 75 the inner edge of the flange 5 to limit the outward motion of each slide, as will be clearly evident. The construction and arrangement of the remaining parts of the said two constructions of cigar-piercing devices illustrated 80 in said Figs. 6 to 9, inclusive, and not here more particularly described are the same as that set forth in the above in connection with the construction of cigar-piercing device represented in Figs. 1 to 5, inclusive. The manner 85 of manipulating the said two devices (represented in Figs. 6, 7, 8, and 9) for piercing the sides of the drawing end of a cigar is precisely the same as that hereinabove set forth in the description of Figs. 1 to 5, inclusive. 90

I am fully aware that many changes may be made in the various arrangements and combinations of parts, as well as in the details of the construction thereof, without departing from the scope of my present invention. Hence I 95 do not limit my invention to the exact arrangements and combinations of the parts as described in the foregoing specification and as illustrated in the accompanying drawings, nor do I confine myself to the exact details of 100 the construction of the said parts.

Having thus described my invention, what I claim is—

1. A cigar-piercer for piercing perforations in the sides of a cigar, comprising a casing, 105 consisting of a pair of shells, each shell being provided with a centrally-disposed opening, either of which is adapted to receive the end of the cigar, holding-flanges on each shell, said flanges being provided with oppositely-placed openings, guides struck up from one of said shells and forming an integral part of the shell, a pair of oppositely-placed slides held in position by said guides, finger-pieces on said slides projecting from the openings in said flanges, and a piercing member connected with each slide and a stop on each slide adapted to be brought in engagement with the inner surfaces of the sides of one of said shells to limit the outward-sliding movements of said slides, substantially as and for the purposes set forth.

2. A cigar-piercer for piercing perforations in the sides of a cigar, comprising a casing, 125 consisting of a pair of shells, each shell being provided with a centrally-disposed opening, either of which is adapted to receive the end of the cigar, holding-flanges on each shell, said flanges being provided with oppositely-placed openings, guides struck up from one of said shells and forming an integral part of the shell, a pair of oppositely-placed slides held in position by said guides, finger-pieces on said slides projecting from the open-

- ings in said flanges, and a piercing member connected with each slide, a stop on each slide to limit its outward movement, and a spring between said slides for normally forcing said slides in opposite directions, substantially as and for the purposes set forth.
3. The herein-described cigar-piercing device comprising a pair of shells 2 and 3, a flange 4 on said shell 2 and a flange 5 on said shell 3, the said flange 4 being provided with an opening and the flange 5 with a projection adapted to be forced into the opening in said flange 4, the said flanges also being provided with oppositely-placed openings 10, a pair of oppositely-placed slides between said shells, a finger-piece on each slide extending from an opening 10, and a piercing member connected with each slide, substantially as and for the purposes set forth.
- 20 4. The herein-described cigar-piercing device, comprising a pair of shells 2 and 3, a flange 4 on said shell 2 and a flange 5 on said shell 3, the said flange 4 being provided with an opening and the flange 5 with a projection adapted to be forced into the opening in said flange 4, the said flanges also being provided with oppositely-placed openings 10, a pair of oppositely-placed slides between said shells, a finger-piece on each slide extending from an opening 10, and a piercing member con-

nected with each slide, and guides on said shells for retaining said slides in proper positions, substantially as and for the purposes set forth.

5. The herein-described cigar-piercer, comprising a pair of shells 2 and 3, a flange 4 on said shell 2 and a flange 5 on said shell 3, the said flange 4 being provided with an opening and the flange 5 with a projection adapted to be forced into the opening in said flange 4, the said flanges also being provided with oppositely-placed openings 10, a pair of oppositely-placed slides between said shells, a finger-piece on each slide extending from an opening 10, and a piercing member connected with each slide, guides on one of said shells for retaining said slides in proper positions, a stop on each slide to limit its outward movement, and a spring between said slides for normally forcing said slides in opposite directions, substantially as and for the purposes set forth.

In testimony that I claim the invention set forth above I have hereunto set my hand this 26th day of September, 1902.

WILLIAM J. BAILEY.
